UNITED STATES PATENT OFFICE.

WILLIAM T. VAN DORN, OF CHICAGO, ILLINOIS.

CAR-AXLE AND METHOD OF REPAIRING CAR-AXLES.

1,272,581.

Specification of Letters Patent. Patented July 16, 1918.

Application filed March 19, 1918. Serial No. 223,341.

To all whom it may concern:

Be it known that I, WILLIAM T. VAN DORN, a citizen of the United States, residing at Chicago, county of Cook, and State 5 of Illinois, have invented a certain new and useful Improvement in Car-Axles and Methods of Repairing Car-Axles, and declare the following to be a full, clear, and exact description of the same, such as will 10 enable others skilled in the art to which it pertains to make and use the same, reference being had to the accompanying drawings, which form a part of this specification.

At present car axles for steam and electric railroads are each made out of a single piece of high grade steel forged into shape and then accurately machined at the ends to form seats upon which the car wheels are pressed and projecting journals. The 15 journals extend into journal boxes containing bearings of bronze or other suitable anti-friction material which rest on the journals and transmit the supported load thereto. The end thrust, that is the thrust in the direction 20 of the length of an axle, is taken by collars or annular shoulders at the ends of the journal. The service to which the journals and the collars or shoulders are subjected is very severe and a constant watch is necessary 25 to insure that neither the journals nor their collars wear away to an unsafe degree. The present practice, when a predetermined amount of wear has taken place on the journals or their collars, on an axle, is to press 30 the wheels off of the axle and place them on a new axle.

The present invention, viewed in one of its aspects, has for its object to produce a simple and novel form of axle which will make it 35 unnecessary to discard an axle after its journals have become worn.

In carrying out my invention I form the wearing surface out of a sleeve which is separate from the remainder of the axle but is 40 so intimately united therewith that in operation the axle acts just like a one-piece axle. This sleeve may be applied not only to a new axle in the course of manufacture but also to 45 an axle of the old type whose journals have become worn and to axles originally provided with sleeves which have become worn sufficiently to make it advisable that they be renewed and therefore, viewed in another of its aspects, my invention may be said to have 50 for its object to produce a simple and effective means of repairing worn axles.

By reason of the fact that the wearing surfaces form part of a member which is made separate from the body of the axle, it is possible so to select the materials from which 60 the body member and the sleeve members of an axle are made that high wearing qualities in the journal will be combined with a high capacity in the body of the axle to resist bending, twisting and other stresses to 65 which axles are subjected; and consequently, viewed in one of its aspects, my invention may be said to have for its object the production of a composite car axle possessing to the highest degree the capacity to resist the wear 70 of a bearing surface and also the stresses to which a beam is or may be subjected.

The various features of novelty whereby my invention is characterized will herein-after be pointed out with particularity in 75 the claims; but, for a full understanding of my invention and of its objects and advantages, reference may be had to the following detailed description taken in connection with the accompanying drawings, 80 wherein:

Fig. 1 is a side elevation of one end of a wheeled car axle arranged in accordance with one form of the present invention, one of 85 the wheels being shown in section;

Fig. 2 is an elevation of one end of an axle properly shaped to receive the bearing sleeve which is shown in section in position to be slipped upon the end of the axle;

Fig. 3 is a view similar to Fig. 2 showing 90 the sleeve in place on the axle;

Fig. 4 is a side elevation of the parts shown in Figs. 2 and 3, after the sleeve has been machined so as to shape a portion of it into a journal having thrust bearings or shoulders at the ends;

Fig. 5 is an elevation of one end of a modified form of axle, the sleeve being shown in section;

Fig. 6 is a side elevation of one end of an 100 axle similar to that shown in Fig. 2 having depressions or grooves in the periphery to secure mechanical interlocking between the axle and the sleeve;

Fig. 7 is an elevation of the end of a completed axle having a body member like that shown in Fig. 6, the sleeve being shown in section; and

Fig. 8 is a view similar to Fig. 6, showing 105 a still further modification.

Referring to Figs. 1 to 4 of the drawings, 1 represents a car axle of any usual or pre-

ferred size and configuration. The axle is machined so as to produce at the extreme ends cylindrical portions, 2, smaller in diameter than the desired journal and of approximately the length of the journal, together with cylindrical portions, 3, somewhat smaller in diameter than the body of the axle at the inner ends of the members 2. Each of the members 3 may be of any desired length. In the arrangement shown, it is long enough to extend well into the hub of the wheel; the line 4 in Fig. 1 representing the inner end or base of the member 3 and being substantially at the middle of the hub of the wheel 5. The meeting ends of the members 2 and 3 are preferably so shaped as not to produce an abrupt shoulder at this point. In the arrangement which I prefer, the outer end of the member 3 is tapered into the form of a frustum of a cone whose elements make an angle of about forty-five degrees with the axis.

The axle heretofore described may be either a new axle which is in the process of being manufactured, or it may be an old axle of the one-piece type or of the composite type comprising the present invention whose journals have become worn and which it is desired to be repaired. In order to complete the axle I place upon each end thereof a sleeve such as indicated at 7 in Fig. 2, the sleeve being preferably made slightly larger in external diameter than the inner end or base of the part 3 and of a length slightly greater than the combined lengths of the parts 2 and 3; the sleeve being bored out in the interior so as to have at one end a bore, 8, of the same length as the part 2 but somewhat smaller in diameter than the latter and at the other end a bore, 9, the same length as the part 3 but somewhat smaller in diameter than the latter, the inner end of the bore 9 terminating in a cone-shaped part, 10, corresponding to the part 6. The sleeve is telescoped upon the end of the axle in such a way that it will be held in place with a strong radial pressure exerted inwardly by the sleeve upon the inclosed core, which pressure is maintained by a tension in the metal of the sleeve. While it is possible to force the sleeve on the axle in a cold state, by using a heavy hydraulic pressure; and while the heat that will be developed in the journal during ordinary service or in case of a hot box, even if sufficient to expand that part of the sleeve surrounding the member 2 of the axle, would not and could not influence that portion of the sleeve surrounding the part 3 of the axle sufficiently to permit the sleeve as a whole to become loose; I prefer to heat the sleeve and shrink it upon the axle. Where the shrinking process is employed, the bore of the sleeve may be made so small 65 in diameter that it cannot be pressed upon the

axle without first heating it to a very high temperature in order to expand the bore sufficiently. Consequently the temperature to which the sleeve will be raised during the process of manufacture will be so much greater than any temperature to which it could possibly thereafter be raised during the use of the axle, that the sleeve could not accidentally be expanded sufficiently to permit it to become loose.

After the parts of the axle have been assembled, as shown in Fig. 3, the exterior of the sleeve is fashioned to give it the contour of the usual journal, 8, having the thrust collars or shoulders, 9 and 10, as shown in Fig. 4.

An axle made in the manner just described will be fully as strong as a one-piece axle because it will withstand shearing and bending stresses just as effectively as the latter and, because the sleeve may be made of a material which will be more durable as a wearing surface than is the material of which axles are now made, the axle as a whole will be superior to the ordinary axle. Then, when the journal becomes worn, instead of throwing away the entire axle, all that it is necessary to do is to slot or split the worn sleeve longitudinally and pry it from the central core so that a new sleeve may be applied as heretofore explained.

In Fig. 5 I have illustrated a slight modification, the only difference between the construction there shown and that previously described being that the part 3^a of the axle, corresponding to the part 3 of the other form, is made so short that it does not enter the hub of the wheel; the entire sleeve, 11, therefore lying beyond the wheel hub.

In some cases it may be advisable so to shape the surfaces of those parts of the axle that are surrounded by the sleeve that when the sleeve shrinks it will be mechanically interlocked with the axle. The mechanical interlock may be arranged to prevent relative movements between the parts in the direction of the length of the axis or angularly around the axis, or both. Axial displacement of the sleeve may readily be prevented by employing shallow grooves extending around the core member of the axle and, if these grooves are made in the form of spirals, some inclined in the opposite direction from the remainder, a positive interlock between the sleeve and core members of the axle against relative rotation, as well as against relative axial movements will be secured.

In Figs. 6 and 7 I have illustrated an arrangement in which the axle member 2^b has thereon two shallow spiral grooves, 12 and 13, inclined oppositely to each other. These grooves may cover any desired portion of the surface of the member 2^b. In the arrangement shown, each of the spirals con-

sists of only a few turns. If desired, an annular groove, 14, may be placed in the member 2^b at such a point that it will lie directly within that portion of the sleeve

5 out of which the collar 9 will be made. Furthermore, if desired, any desired number of grooves, 15, may be placed on the part 3^b of the axle.

If desired, the interlocking means may be 10 applied entirely to one or the other of the core members of the axle. A simple way of securing interlocking is to provide the part 3^c , as shown in Fig. 8, with two series of crossing shallow spiral grooves, 16 and 15 17. If desired, the grooves may be in the form of a fine thread as indicated at 18 and 19 on the part 2^c in Fig. 8.

It will be seen that when the hot expanded sleeve is placed over the central 20 core which has been prepared with grooves or recesses, the metal of the sleeve, upon cooling, will enter the grooves or recesses and, if the latter are not too deep, completely fill them; so that there will be an 25 effective mechanical interlock between the sleeve and the body member of the axle, and the sleeve and the axle will be to all intents and purposes a single integral piece and no separation can occur without slotting or splitting the sleeve and prying it 30 open.

It will of course be understood that the higher the temperature to which the sleeve is heated when it is applied, the easier it 35 will be to force it home to its seat and the tighter will be its grip on the axle. Where the surface of the core member is roughened or grooved it is additionally important that the initial temperature be high in order to 40 prevent the core from scraping metal from the interior of the sleeve and filling the depressions or grooves with loose metal. In fact I prefer to heat the sleeve to a temperature just short of a welding heat and 45 then drive it onto the core by means of a single quick blow which will seat the sleeve before the interior has an opportunity to begin to chill through contact with the core.

Where it may be deemed advisable to 50 secure a stronger mechanical interlock than will result from the mere contraction of the hot sleeve so as to cause the metal at the interior thereof to flow into the grooves or recesses in the core member of the axle, the 55 sleeve may be squeezed or compressed about the core while still extremely hot so as to cause the metal to flow positively into the grooves or recesses. This may readily be accomplished by allowing the sleeve to seat 60 itself in a die surrounding the core of the axle just before the sleeve seats itself in its final position on the axle or by causing jaws to close upon the sleeve as it is seating itself or immediately afterward. Where the hot 65 sleeve is compressed in the manner just de-

scribed, the grooves or recesses may be made deeper than it would be possible to fill through the mere contraction of the hot sleeve.

I claim:

1. A car axle having at the end a reduced portion, and a sleeve having at its outer end the exterior contour of a completed journal provided with end thrust collars pressed on said reduced portion and held thereon by 70 radial pressure produced and maintained by tension in the metal of the sleeve, said reduced portion and said sleeve being sufficiently longer than the journal that a portion of the sleeve will grip the axle without 75 being influenced by the conditions in the zone occupied by the journal.

2. A car axle having at the end a reduced portion considerably longer than a completed journal and a sleeve fitting upon said 85 reduced portion and being in a state of tension caused by the tendency of the sleeve to contract until its interior diameter is considerably less than that of the reduced portion so that the sleeve is held on the axle 90 by pressure maintained by the tension in the sleeve, said sleeve having its outer end fashioned so as to have the contour of a complete car axle journal, and the inner end of the sleeve extending sufficiently beyond the 95 zone occupied by the journal to prevent the conditions at the journal from influencing the grip at the inner end of the sleeve.

3. The method of producing a journal on a car axle which consists in forming on the 100 axle a portion of reduced diameter extending inwardly from an end of the axle for a distance considerably longer than a completed journal, making a sleeve having an internal diameter considerably smaller than 105 the diameter of the reduced portion of the axle, telescoping the sleeve upon the said reduced portion in such a manner that the sleeve grips the axle with a strong radial pressure, and finally finishing the sleeve to 110 give the outer end of it the shape of a complete car axle journal.

4. A car axle having at the end a reduced portion forming with the body of the axle an abrupt shoulder, said reduced portion 115 terminating at its outer end in a rudimentary journal of still smaller diameter gradually merged into that part of the reduced portion of larger diameter than the rudimentary journal so as to avoid an abrupt 120 shoulder, and a sleeve having at its outer end the contour of a complete car axle journal surrounding said reduced portion including the rudimentary journal and held thereon by radial pressure produced and 125 maintained by tension in the metal of the sleeve, the sleeve fitting at its inner end against the aforesaid shoulder.

5. A car axle having at the end a portion of reduced diameter provided with depre- 130

11. A car axle having at the end a portion of reduced diameter provided with depressions in the periphery, and a sleeve having the exterior contour of a complete car axle journal shrunk upon said portion of reduced diameter and having the metal thereof projecting into said recesses, the construction and arrangement of the recesses being such as to produce a mechanical interlock which will prevent relative movements between the sleeve and the axle independently of the resistance to such movement afforded by the grip which the sleeve has upon the surface of the surrounded portion of the axle. 70
12. A car axle having at the end a portion of reduced diameter and a rudimentary journal of still smaller diameter at the outer end of said reduced portion, said reduced portion having recesses in the periphery thereof, and a sleeve having at its outer end the exterior contour of a complete car axle journal, said sleeve surrounding said reduced portion and said rudimentary axle and having the metal thereof extending into said recesses, said recesses being constructed and arranged to prevent relative movements between the sleeve and the axle in the axial direction. 80
13. A car axle having at the end a portion of reduced diameter and a rudimentary journal of still smaller diameter at the outer end of said reduced portion, said reduced portion having recesses in the periphery thereof, and a sleeve having at its outer end the exterior contour of a complete car axle journal, said sleeve surrounding said reduced portion and said rudimentary axle and having the metal thereof extending into said recesses, said recesses being constructed and arranged to prevent relative rotary movements between the sleeve and the axle in the axial direction. 90
14. A car axle having at the end a portion of reduced diameter provided with shallow right and left hand peripheral spiral grooves, and a sleeve having the exterior contour of a complete car axle journal surrounding said reduced portion and having the metal thereof extending into said grooves. 100
15. The method of producing a journal on a car axle which consists in forming at the end of the axle a portion of reduced diameter having shallow recesses in its periphery, driving on said reduced portion a sleeve heated to a high temperature so as to expand the bore to the aforesaid diameter and, upon cooling, shaping the sleeve so as to give it the exterior contour of a complete car axle journal. 110
16. The method of producing a journal on a car axle which consists in forming at the end of the axle a portion of reduced diameter, heating a sleeve having an interior 120
- sions in its surface, and a sleeve having the exterior contour of a complete journal surrounding said portion of reduced diameter and having the metal thereof extending into said depressions, the construction and arrangement of the depressions being such that the sleeve and the axle are interlocked against relative axial movements and against rotary movements. 5
10. 6. A car axle having at the end a portion of reduced diameter provided with depressions in its surface, and a sleeve having the exterior contour of a complete journal surrounding said portion of reduced diameter and having the metal thereof extending into said depressions, the construction and arrangement of said depressions being such as to prevent relative rotary movements between the axle and the sleeve. 15
20. 7. A car axle having at the end a portion of reduced diameter provided with depressions in its surface, and a sleeve having the exterior contour of a complete journal surrounding said portion of reduced diameter and having the metal thereof extending into said depressions, the construction and arrangement of the depressions being such that the sleeve and the axle are interlocked against relative axial movements and against rotary movements, said sleeve being held in place by radial pressure produced and maintained by tension in the metal of the sleeve. 30
35. 8. A car axle having at the end a portion of reduced diameter provided with shallow peripheral grooves, and a sleeve having the exterior contour of a complete car axle journal surrounding said reduced portion and having the metal thereof projecting into said grooves, the construction and arrangement of the grooves being such that the sleeve and the axle are interlocked against relative axial movements and against relative rotary movements. 40
45. 9. A car axle having at the end a portion of reduced diameter provided with shallow peripheral grooves, and a sleeve having the exterior contour of a complete car axle journal surrounding said reduced portion and having the metal thereof projecting into said grooves, the construction and arrangement of the grooves being such that the sleeve and the axle are interlocked against relative axial movements and against relative rotary movements, said sleeve being held in place by radial pressure produced and maintained by tension in the metal of the sleeve. 50
55. 10. A car axle having at the end a portion of reduced diameter provided with depressions in the periphery, and a sleeve having the exterior contour of a complete car axle journal shrunk upon said portion of reduced diameter and having the metal thereof projecting into said recesses. 60

bore considerably smaller in diameter than the aforesaid diameter to a temperature approaching a welding heat, then driving the sleeve onto said part of reduced diameter by 5 a quick blow, and finally finishing the sleeve to give it the shape of a complete car axle journal after it has become cool.

17. The method of producing a journal on a car axle which consists in forming at 10 the end of the axle a portion of reduced diameter having in the surface depressions or grooves constructed and arranged to prevent relative rotary and axial movements between the axle and a sleeve having parts 15 extending into said depressions or grooves, placing on said reduced portion a sleeve heated to a high temperature so as to expand the bore to the aforesaid diameter and, upon cooling, shaping the sleeve so as to 20 give to it the exterior contour of a complete car axle journal.

18. The method of producing a journal on a car axle which consists in forming at the end of the axle a portion of reduced diameter having recesses in the periphery thereof, placing on said portion of reduced diameter a sleeve and causing the material of the sleeve to enter said recesses, the recesses being constructed and arranged to 30 prevent relative movements between the axle and the sleeve, and shaping the sleeve so as to give it the exterior contour of a complete car axle journal.

19. The method of producing a journal 35 on a car axle which consists in forming at the end of the axle a portion of reduced diameter having recesses in the periphery thereof, heating to a temperature approaching a welding heat a sleeve having a smaller 40 internal diameter than the aforesaid diameter, driving the sleeve onto said portion of reduced diameter, and allowing the sleeve to cool and shrink into said recesses.

20. The method of producing a journal on 45 a car axle which consists in forming at the end of the axle a portion of reduced diameter having recesses in the periphery thereof, driving on said reduced portion a sleeve

heated to a high temperature so as to expand the bore to the aforesaid diameter and, 50 while the sleeve is still hot, applying pressure to the exterior of the sleeve to set the metal at the interior thereof into said recesses.

21. The method of producing a journal 55 on a car axle which consists in forming on the axle a portion of reduced diameter considerably longer than a completed journal, making a sleeve having an internal diameter considerably smaller than the diameter of 60 the reduced portion of the axle, heating the sleeve to a high temperature, forcing the hot sleeve onto the reduced portion of the axle, and finally finishing to give the outer end of it the shape of a complete car axle journal 65 after the sleeve has become cool.

22. The method of producing a journal 70 on a car axle which consists in forming on the axle a portion of reduced diameter, making a thick sleeve having an internal diameter considerably smaller than the diameter of the reduced portion of the axle, telescoping the sleeve upon the said reduced portion in such a manner that the sleeve 75 grips the axle with a strong radial pressure, and then turning down the exterior of the sleeve so as to form about the periphery thereof annular thrust surfaces or shoulders facing each other.

23. The method of producing a journal 80 on a car axle which consists in forming on the axle a portion of reduced diameter, making a thick sleeve having an internal diameter considerably smaller than the diameter of the reduced portion of the axle, heating 85 the sleeve to a high temperature, forcing the hot sleeve onto the reduced portion of the axle, and finally turning down the exterior of the sleeve after it has become cool 90 so as to form about the periphery thereof annular thrust surfaces or shoulders facing each other.

In testimony whereof I sign this specification.

WILLIAM T. VAN DORN.
